DEVICE FOR WASHING PHOTOGRAPHIC PRINTS

Frederick C. Schnelz, Detroit, Mich.

Application April 9, 1937, Serial No. 135,863

4 Claims. (Cl. 95—97)

The present invention relates to washing or spray devices generally, and in particular provides an improved device for washing photographic prints or the like.

5 A relatively wide variety of devices have heretofore been proposed for the purpose of washing photographic negatives or prints, following the treatment thereof with developing solutions. Conventionally, the washing operations are effected in trays or pans, and the devices in question may take the form of nozzles or sprays which are designed to cause a circulation of the water over and past the negatives or prints in order to remove all traces of the developing solution 10 therefrom. An illustrative arrangement of this kind is shown in the Nichols Patent No. 1,136,705, granted April 20, 1915.

Devices of the Nichols type, however, as well as others, of which the present applicant is 20 aware, are objectionable either in that they do not effectively maintain the water in circulation relative to the negative or prints, in that they permit the negatives or prints to become stuck together, or in that they cannot readily be adjusted to modify the circulating effect or to adapt them to differing constructions of washing trays or pans. The present invention is directed primarily to the provision of a washing device which 25 completely overcomes all of the just noted objections, as well as others.

With the foregoing considerations in view, objects of the present invention are to provide a device of the above indicated character, adapted to both maintain a washing solution in circulation and keep prints or negatives or the like separated from each other; to provide such a device which is readily adjustable to modify the circulating and separating effects; to provide such a device which is readily adjustable to different depths of washing trays or pans; to provide such a device which may be readily secured to and separated from washing trays or pans of different sizes and constructions; to provide such a device embodying a clamping member adapted 40 to be secured to a washing tray or pan, and embodying a spray or nozzle member having one or more rows of orifices through which angularly displaced streams of water may be directed to cause a circulation within the tray or pan and 45 also to cause the prints or negatives to remain separated from each other.

With the above, as well as other objects, in view, a preferred but illustrative embodiment of the invention is shown in the accompanying 50 drawing, throughout the several views of which

corresponding reference characters are used to designate corresponding parts and in which:

Figure 1 is a view in front elevation of a typical photographic washing arrangement;

Fig. 2 is a view in vertical section of the improved washing device; and

Fig. 3 is a plan view, taken along the line 3—3 of Fig. 2.

Referring first to Fig. 1, it will be appreciated that photographic or similar washing operations 10 are conventionally effected by depositing the negatives or prints, or other specimens, as the case may be, within a tray or pan 10, which in turn is deposited within a collecting device such as the sink 12. The washing solution, conventionally water, is supplied to the tray 10 through a hose 14, and a nozzle structure 16, to the construction and arrangement of which the present invention is primarily directed. The water is circulated within the tray or pan 10 by the nozzle structure 16, and overflows from the tray 10 into the sink 12.

Referring more particularly to Figs. 2 and 3, the device 16 comprises a nozzle member 18 which is removably and adjustably secured to the 25 side wall of the pan or tray 10 by means of the clamp 20. The nozzle member 18 is illustrated as being of tubular form, one end of which is received within the end of the hose 14, and the lower end of which is closed, as by a suitable 30 plug (not shown). Preferably and as illustrated, at least two separate rows of orifices 18a and 18b are provided in the side wall of the tube 18, the two rows being in angularly spaced relation to each other. With this arrangement, and 35 by rotating the nozzle 18 to the position shown in Fig. 3, a plurality of streams of water may be caused to issue from the orifices 18a in a direction generally parallel to the side wall 10a of the tray or pan 10. These streams of water 40 effect a circulation of the water around the pan, causing it to flow continuously and without substantial turbulence over any negatives or prints or other specimens which may be disposed within the pan. At the same time, a corresponding 45 series of streams of water may be caused to issue from the orifices 18b in a direction generally transverse of the wall 10a, which streams of water impinge upon the edges of the prints or negatives and tend to flow between the successive layers of the prints or negatives. This 50 action is found in practice to effectively keep the prints or negatives freely separated, thus insuring that the entire surface of each print or negative is completely washed by the water.

The bracket or clamp 20 comprises a generally U-shaped body having the spaced legs 22 and 24, which are adapted to be fitted over the side wall 10a, of the tray 10. The inner face of the leg 24 is preferably formed to abut a substantial area of the surface of the walls 10a, so that a tilting or rocking of the clamp is prevented, and the outer leg 22 is provided with a threaded opening 26, to receive a locking stud 28. The inner end 10 of stud 28 bears against the outer face of the wall 10a, and may be turned between the locking and released position by a conventional knurled head 30. Preferably, the spacing between the legs 22 and 24 is great enough to accommodate the clamp 15 to a pan or tray having a relatively large bead such as the bead 10b.

In order to accommodate the nozzle 18, the bracket 20 is provided adjacent its upper edge with a boss 32, which is bored to freely, slidably 20 and rotatably receive the nozzle 18. A locking stud 34 is received within the threaded opening provided in the boss 32, and may be turned inwardly or outwardly by the knurled head 36 to either lock the nozzle 18 in a selected position 25 of adjustment or to release the nozzle 18. In the locked position, it is noted that the inner end of the stud 32 bears directly against the side wall of the nozzle 18.

It will be appreciated that the complete device 30 may be readily and economically manufactured. It will also be appreciated that it may be readily and quickly applied to and removed from trays or pans of widely varying constructions, and that, in the clamped position on a tray or pan, it is 35 rigidly held against tilting or rocking. It will also be appreciated that the provision of the adjustment between the nozzle 18 and the bracket 20 permits the nozzle 18 to be adjusted both vertically, to accommodate it to pans or trays of differing depth, and also permits it to be rotatively 40 adjusted to selectively control the direction of flow of the sprays or streams of water from the several rows of orifices.

Although a specific embodiment of the invention has been described, as well as a specific application or use therefor, it will be appreciated that the invention may be applied to uses other than those specified, and may be embodied in forms differing widely from the illustrated form.

What I claim is:

50 1. In a device of the character described, for use with a tray or like container adapted to re-

ceive photographic specimens or the like, a combination of a tubular nozzle member adapted to be projected into said tray, said nozzle member having a first substantially vertical row of orifices through which liquid may be discharged to effect a circulation within the container, and having a second substantially vertical row of orifices through which liquid may be discharged in substantially horizontal streams to maintain said specimens in a separated condition, said rows being 10 angularly displaced from each other.

2. In a device of the class described, the combination of a tubular nozzle adapted to project into a tray or like container and having one or more orifices in the side wall thereof through 15 which liquid may be projected into said container, a bracket having a boss within which said tubular nozzle is rotatably and slidably received, said bracket having a U-shaped portion adapted to fit over the side of said container, and means for 20 locking said bracket to said container and for locking said nozzle within said bracket.

3. A device for use in the washing of photographic prints comprising, in combination, a bracket adapted to engage over the side of a 25 container, means for releasably and rigidly securing said bracket to the side of said container, a nozzle member provided with a plurality of orifices therein adapted to eject streams of liquid 30 therefrom in the same general plane, said nozzle member being axially adjustable relative to said bracket whereby to permit its vertical relation with respect to the bottom of said container to be varied, and means for releasably and rigidly securing said nozzle member in axially adjusted 35 relation with respect to said bracket.

4. A device for use in the washing of photographic prints comprising, in combination, a bracket adapted to engage over the side of a 40 container, means for releasably and rigidly securing said bracket to the side of said container, a nozzle member provided with a plurality of orifices therein adapted to eject streams of liquid 45 therefrom in the same general plane, said nozzle member being rotatably adjustable relative to said bracket whereby to permit the angular relation of said streams with respect to said container to be varied, and means for releasably and rigidly securing said nozzle member in rotatably adjusted relation with respect to said bracket.
